UNITED STATES PATENT OFFICE.

JAMES CLAYTON, OF COVENTRY, ENGLAND, ASSIGNOR TO COURTAULDS, LIMITED, OF LONDON, ENGLAND.

DEVICE TO BE EMPLOYED IN MAKING FUNNELS, OR THREAD-GUIDES, FOR USE IN MACHINES FOR THE MANUFACTURE OF ARTIFICIAL SILK.

1,224,071.

Specification of Letters Patent. Patented Apr. 24, 1917.

Original application filed April 18, 1916, Serial No. 91,988. Divided and this application filed August 17, 1916. Serial No. 115,528.

To all whom it may concern:

Be it known that I, JAMES CLAYTON, a subject of the King of Great Britain, residing at 12 Middleborough road, Coventry; in 5 the county of Warwick, England, have invented a new and useful Device to be Employed in Making Funnel, or Thread-Guides, for Use in Machines for the Manufacture of Artificial Silk, of which the following is a specification.

This invention consists in a device whereby funnels, or thread-guides (for use in machines for the manufacture of artificial silk, to guide the thread into the rotating spinning boxes) furnished (according to my invention the subject of an application for patent filed by me on April 18, 1916, and bearing Serial No. 91,988, of which the present application is a division) with a 15 ferrule, or sleeve, which surrounds that part of the said funnel, or thread-guide, which is to be supported through the medium of the ferrule, or sleeve, in the fitting, or bearing, of the machine, the said ferrule, or sleeve, 20 being affixed to the funnel, or thread-guide, while it is held in a device such that the longitudinal axis of the said ferrule, or sleeve, 25 is supported in the same line as that in which the axial lines or centers, of the aforementioned upper and lower supports are situated.

The said device consists of an upright provided at top, with a projecting arm, and at bottom with another projecting arm, the distance between these arms being sufficient 30 to support between, preferably cone-ended, bearing pieces the funnel, or thread-guide, one of the said bearing pieces being carried by the lower arm and the other of the said bearing pieces being a rod capable of sliding in an opening in the upper arm in which it can be fixed by means of a set-screw, or the like. Carried by the said upright is an intermediate arm at the distance from the lower bearing point in accordance with the 35 distance from the lower end of the tubular part of the funnel, or thread-guide, at which the ferrules, or sleeves, are to be fixed on all the funnels, or thread-guides, so that the length of the tubular part of the funnel, or 40 thread-guide, below the upper part of the ferrule, or sleeve, is the same in all cases. The holes in the three arms, namely the two

for the supports, and the one for the reception of the ferrule, or sleeve, are bored so that their longitudinal axes are all in one 55 straight line.

When the funnel, or thread-guide, and the ferrule, or sleeve, are supported in the manner described, a substance which can by heat, or otherwise, be brought to a condition 60 so that it is pourable and will set sufficiently (such as pitch) is poured into the space between the ferrule, or sleeve, as described in the specification of my aforesaid application.

The accompanying drawing shows a device constructed in accordance with my invention:

Figure 1 shows the funnel, or thread-guide, for the making of which the said device is used, Fig. 2 is a sectional elevation and Fig. 3 is a transverse section, (on the line A, B, Fig. 2) of the device showing a funnel, or thread-guide, provided with a ferrule, or sleeve, supported therein.

1, is tubular part of the funnel, or thread-guide, and 2, is the enlargement, or cup, part, at top. The ferrule, or sleeve, is marked 3.

The device constituting this invention is 80 constructed and used as follows:

An upright 4, is formed at top with a projecting arm 5, and at bottom with a projecting arm 6. The lower arm 6, carries a cone-ended bearing piece, 7, and the upper arm carries a cone-ended bearing piece constituted by the rod 8, capable of sliding in the upper arm 5, the said rod being shown provided with a knob 8^a, for convenience of manipulation and being fixable in position 85 by a set-screw 9. The arm which carries the ferrule, or sleeve, 3, to be fixed to the funnel, or thread-guide, is marked 10. It is shown as being made in two parts secured together by a hinge pin 10^a, and is formed with an opening to receive and fit the said ferrule, or sleeve, one portion of which opening is in the fixed part of the arm, the other portion of the said opening being in the part of the arm which can be turned 90 upon the hinge-pin 10^a. When the funnel, or thread-guide, and ferrule, or sleeve, are in place the movable part of the arm 10, is turned against the fixed part and the two

parts are secured together by a screw, or clip. In the drawing a wire clip 11, is shown for this purpose.

When the parts are thus secured pitch, 5 or other suitable substance, is introduced to the space between the inside of the ferrule, or sleeve, 3, and the outside of tubular part of the funnel, or thread-guide, as shown at 12, a rubber-band, or some material such as 10 putty, for example, being applied to the lower part of the space to retain the pitch till it is set.

What I claim is:—

1. A device for affixing a ferrule to a 15 tubular thread guide, comprising means engaging the upper and lower ends of the tubular guide to hold the latter in predetermined axial position and clamping means for holding a ferrule surrounding the guide 20 but spaced therefrom to receive an interposed cement.

2. A device for affixing a ferrule to a 25 tubular thread guide, comprising members relatively displaceable to permit the insertion therebetween of the upper and lower ends of the tubular guide and to hold the latter in predetermined axial position in combination with means for holding a ferrule surrounding the guide but spaced therefrom to receive an interposed cement.

3. A device for affixing a ferrule to a 30 tubular thread guide, comprising means en-

gaging the upper and lower ends of the tubular guide to hold the latter in predetermined axial position, a fixed support for 35 holding a ferrule in coaxial position on said guide but spaced therefrom to receive an interposed cement, together with a coöperating movable member serving to clamp 40 said ferrule between the same and the fixed support.

4. A device for affixing a ferrule to a 45 tubular thread guide, comprising means engaging the upper and lower ends of the tubular guide to hold the latter in predetermined axial position, a fixed support having a ferrule-receiving groove coaxial with the tubular guide.

5. A device for affixing a ferrule to a 50 tubular thread guide, comprising centering devices for engaging the opposite ends of the guide and holding the same in predetermined axial position, in combination with a fixed ferrule support having a ferrule-receiving groove coaxial with said centering devices.

In testimony whereof I have signed my name to this specification in the presence of two subscribing witnesses.

JAMES CLAYTON.
